Primary Examiner — Kevin Rudzinski(74) *Attorney, Agent, or Firm* — Wenderoth, Lind & Ponack, L.L.P.(57) **CLAIM**

The ornamental design for an accessory for a lamp, as shown and described.

DESCRIPTION

FIG. 1 is a left view of the invention;

FIG. 2 is a front view of the invention;

FIG. 3 is a top view of the invention;

FIG. 4 is a rear view of the invention;

FIG. 5 is a bottom view of the invention;

FIG. 6 is a perspective view of the invention; and,

FIG. 7 is a right view of the invention.
